UNITED STATES PATENT OFFICE.

FRANCIS WILLIAM GOWER, HUGH JAMES OWEN, AND ROBERT JOHN NASH, OF BIRMINGHAM, ENGLAND.

TENNIS RACKET AND THE LIKE.

Application filed June 29, 1923. Serial No. 648,539.

To all whom it may concern:

Be it known that we, FRANCIS WILLIAM GOWER, a subject of the King of Great Britain, residing at "Dunoon," Russell Road, 5 Moseley, Birmingham, in the county of Warwick, England, HUGH JAMES OWEN, a subject of the King of Great Britain, residing at 110 Trinity Road, Birchfields, Birmingham, in the county of Warwick, England, 10 and ROBERT JOHN NASH, a subject of the King of Great Britain, residing at 46 Beaconsfield Road, Cannon Hill, Birmingham, in the county of Warwick, England, have invented certain new and useful Improvements in or Relating to Tennis Rackets and 15 the like, of which the following is a specification.

The present invention comprehends a tennis racket or the like having in combination a frame and a handle formed by bending a single strip of solid section bar to a bow formation and directing extremities in parallel relation to constitute the handle, a spacing piece immovably or permanently secured across the bow or frame at its junction with the limbs of the handle and a wire striking face engaged with apertures in the frame and in the spacing piece.

In order that this invention may be clearly understood and readily carried into practice, reference may be had to the appended explanatory sheet of drawings:—

Figure 1 is a plan view of a tennis racket constructed according to the present invention.

Figure 2 is a longitudinal section taken on line *a—a* of Figure 1.

Figure 3 is a transverse section taken on the line *b—b* of Figure 1.

Figures 4 and 5 illustrate in enlarged section and plan respectively fragments of the frame showing the particular apertures therein.

In a convenient embodiment of the present invention a strip of aluminium or other suitable metal of rectangular flat or solid section is bent to the bow formation to form the frame 1 and its extremities 2 are directed outwardly in parallelism to constitute the handle. This strip may be of slightly reduced transverse measurement at or towards its centre part 3 to obtain the correct balance and strength for the bow. A spacing or wedge-piece 4 is incorporated at the junc-

tion of the bow 1 with the handle 2 between the two limbs. This spacing or wedge piece is of aluminium formed by casting, pressing or other suitable operation and is riveted or otherwise permanently secured in position as for example at 5. This spacing or wedge-piece is in the form of a hollow frame the outer faces of which bear against the inner converging faces of the frame or bow, and the inner element indicated by the numeral 4 completes the bow or frame of the racket. The spacing piece may involve a frame 6 adapted to wedge between the limbs of the handle and be riveted thereto, at the points 5 aforesaid, which frame has integrally formed therewith the curved or segmental part 4 which completes the contour of the bow or frame and is perforated for the wire and gradually diminishes at its extremities into such bow or frame being riveted thereto. The parallel limbs 2 of the handle are transversely drilled for lightness at 7, and are spaced apart by small bridging pieces 8, 9 secured by rivets, screws or the like, and the handle is completed by two sheet metal channel members 10 which are placed between parallel limbs of the handle and adapted to bear on the bridge pieces 8, 9 on each side of the said handle. The bridge piece 8 may be undercut as shown to accommodate the extremities of the members 10. These channel members 10 are afterwards suitably bound or secured in position by any covering or other suitable means and the extremity of the handle is closed by a metal cap 11 and rubber or other cover 12. The bow 1 has a series of perforations 13 around its periphery for the reception of the striking face which involves a high tensile hard steel rustless wire or twisted strand wire 14, threaded through the apertures backwards and forwards in the usual manner. The apertures 13 are subjected at their outer extremities, that is, from outside of the frame to a punching or pressing operation from a pointed die or tool adapted to render the outer extremity of each slot to a fish-tail configuration, as at 15; so that sharp edges are avoided.

In order to bring this wire striking face to the required tension, the frame may be subjected to a mechanical planishing operation in a pressing machine between upper and lower tools which are caused to travel

around the entire frame and the spacing or wedge piece and force the whole outwardly and thereby very efficiently tighten the striking face. Alternatively, the planishing operation may be effected manually.

Instead of such planishing operation to tension the striking face we may employ the method of wiring the frame under tension produced by a temporary deformation 10 of the frame as set forth in our divisional application which has eventuated into Patent 1,545,814, dated July 7, 1925.

The section of the bar or strip may vary considerably; it may be internally or externally grooved and is of a solid character.

In another embodiment of the present invention, a length of extruded bar may be bent to constitute the bow and the handle.

If desired, instead of using ordinary 20 straight wire for the striking face, spirally wound or crinkled wire may be employed to give a flexible striking face. Further, in any of the striking faces aforesaid, lengths of rubber or rubber strip, tubing, or the like 25 may be threaded through the wire striking face with a view to avoiding any sound or noise which may occur upon striking the ball.

In the present invention, an all metal 30 racket or bat is presented with the exception, perhaps, of the binding or gripping surface upon the handle and its rubber extremity and rackets constructed according to this 35 invention can have their striking face tightened at any time should they become slack by the mechanical or other planishing operation, aforesaid.

What we claim as our invention and desire to secure by Letters Patent is:—

1. A tennis racket or the like, having in combination a frame and a handle formed by bending a single strip of solid section bar to a bow formation and directing and fastening its extremities in parallel relation to constitute the handle, an arcuate metal spacing piece secured across the bow frame at its junction with the limbs of the handle to complete the elliptical configuration of the frame and to support, in conjunction with said bow frame, a wire striking face the components of which are engaged with apertures in the frame and in the arcuate piece, said arcuate spacing piece having an integral hollow wedge which fits 55 between the limbs of the handle and is secured thereto.

2. A tennis racket or the like, having in combination a frame and a handle formed by bending a single strip of solid section bar to a bow formation and directing its extremities in parallel relation to constitute the handle, an arcuate piece having an integral hollow wedge secured across the bow frame at its junction with the limbs of the handle, said hollow wedge fitting between

and being secured to said limbs, a wire striking face engaged with apertures in the frame and in the spacing piece, and a number of bridge pieces secured between the said limbs of the handle beyond the said 70 wedge.

3. A tennis racket or the like, having in combination a frame and a handle formed by bending a single strip of solid section bar to a bow formation and directing and fastening its extremities in parallel relation to constitute the handle, an arcuate metal spacing piece secured across the bow frame at its junction with the limbs of the handle to complete the elliptical configuration of the frame, said arcuate piece having an integral hollow wedge frame for fitting between said limbs of the handle, said arcuate piece further supporting in conjunction with the said bow frame a wire striking face the components of which are engaged with apertures in the frame and in the arcuate piece, some of said components engaging said arcuate piece on each side of the wedge, and a number of bridge pieces secured between the limbs of the handle beyond said wedge.

4. A tennis racket or the like having in combination a bent metal bow frame the extremities whereof are continued to constitute the handle, an arcuate spacing piece the ends of which seat against and are secured to the sides of the bow frame, said spacing piece having a rigid wedge frame projecting from it intermediate of its ends which wedge fits between and is secured to the limbs of said handle and terminates at the throat portion of said bow frame and handle, said spacing member thus having a four point attachment across the throat portion of the racket frame, and a flexible striking face for the racket laced in said bow frame and in the arcuate spacing piece.

5. A tennis racket or the like, having in combination a frame and a handle formed from a single strip of solid section bar, having a central part of reduced section tapering from the ends, by bending said tapered strip to a bow formation and directing its extremities in parallel relation to constitute the handle, an arcuate spacing piece secured across the bow frame at its junction with the limbs of the handle, a wedge on said spacing piece, said wedge engaging said limbs and a wire striking face engaged with apertures in the frame and in the spacing piece.

6. A tennis racket or the like, having in combination a frame and a handle formed by bending a single strip of solid section bar, the central part of which is of reduced section tapering from the ends, to a bow formation and continuing the extremities in parallel relation for the full length of a handle, an arcuate metal spacing piece se-

cured across the bow frame at its junction with the limbs of the handle to complete the elliptical configuration of the frame and to support, in conjunction with said bow frame, a wire striking face the components of which are engaged with apertures in the frame and in the arcuate piece, and a number of bridge pieces at intervals between

said limbs upon which hand grip portions are secured.

In witness whereof we have hereunto set our hands.

FRANCIS WILLIAM GOWER.
HUGH JAMES OWEN.
ROBERT JOHN NASH.
